UNITED STATES PATENT OFFICE.

HERMAN F. WULLSTEIN, OF SALT LAKE CITY, UTAH.

SCREEN.

Application filed February 1, 1924. Serial No. 690,046.

To all whom it may concern:

Be it known that I, HERMAN F. WULLSTEIN, citizen of the United States, residing at Salt Lake City, in the county of Salt Lake 5 and State of Utah, have invented certain new and useful Improvements in Screens; and I do declare the following to be a full, clear, and exact description of the invention, such as will enable others skilled in the art 10 to which it appertains to make and use the same.

My invention relates to screens for ore, gravel, sand and numerous other materials and has reference more particularly to 15 screens which are moved to cause proper feeding of the material therethrough.

One object is to provide self-acting means for quickly thrusting the screen upwardly when moved to an inoperative position and released, and a unique cam wheel arrangement for so moving and releasing the thrusting means at spaced intervals, while permitting said means to stand inert between such intervals.

25 Each cam wheel is formed with peripheral cam brought successively into play, and a further aim is to provide novel operating means cooperable with said cams for intermittently turning the wheel.

30 Another object is to make novel provision for varying the intensity of the thrusts imparted to the screen.

Yet another object is to provide a screen 35 thrusting means having unique construction and association with the main frame of the machine.

A still further object is to provide screen 40 thrusting means in two units, for spaced portions of the screen and to provide for operating the cam wheels for these units alternately, or simultaneously, as desired.

Another object is to make novel provision 45 for movably mounting the screen within the main frame.

A still further aim is the provision of a screening machine which will be comparatively simple and inexpensive, will have no working parts exposed to grit and dirt, and will be highly efficient and desirable.

50 With the foregoing in view, the invention resides in the novel subject matter herein-after described and claimed, the description

being supplemented by the accompanying drawings.

Figure 1 is a top plan view of a vibrating 55 screen constructed in accordance with my invention.

Figure 2 is a side elevation.

Figure 3 is an end elevation.

Figure 4 is a vertical longitudinal sec- 60 tional view, as indicated by line 4—4 of Figure 1.

In the drawings above briefly described, the numeral 1 designates a main frame, and while illustrated in horizontal position, is 65 intended in most instances to be inclined to insure proper feeding of the material along the screening means. The frame 1 is provided with a pair of parallel side bars 2 which are formed of channel metal with 70 their channels disposed inwardly. At one end the bars 2 are connected by a transverse bar 3^a and landing plate 3 to receive the material being screened, while a transverse end bar 4 connects the other ends of said 75 side bars. If desired, a relatively narrow bar 5 may also connect the last mentioned ends of the side bars 2 and may have its ends extended to provide handles or trun- 80 nions 6.

Disposed longitudinally within the channels of the side bars 2 are two parallel screens supporting bars 7 which, in the present disclosure, are secured to transverse bars 8 whose ends project beyond the bars 7 through notches 9 in the lower edges of the bars 2, the projecting ends of said bars 8 being connected by longitudinal bars 10 85 having central shoes 11 on their upper sides. The ends of the bars 8 and conse- 90 quently the bars 10 and 7, are supported by compression springs 12 seated within suitable saddles 13 which are secured to the bars 2 at the open lower ends of the notches 9, the strength of said springs being ad- 95 justable by set screws or the like 14. By means yet to be described, the bars 10, 8 and 7 are intermittently depressed against the action of the springs 12 and then re- 100 leased, causing said springs to quickly force the bars upwardly, thus forcibly thrusting upwardly on the screen supported by said bars.

This screen may be of woven or other desired formation, but it may well be constructed

— of a plurality of spaced longitudinal fingers 15 extending from transverse carrying bars 16 whose ends extend into the channels of the side bars 2. These ends may in some instances be suitably guided for vertical movement and free of connection with the bars 7, but in the present disclosure, the bars 16 may be considered as secured to said bars 7.

10 To limit the upward movement of the screen, I have shown a pair of angle metal bars 17 secured in the channels of the side bars 2 and provided with stop flanges in the upward paths of the bars 16. Guard plates 18 preferably contact with the inner edges of the top flanges of the bars 2 and with the corresponding edges of the bars 17, the lower portions of said plates 18 having flanges 19 resting on the bars 17 to hold said plates against downward movement. Movement in other directions is prevented by bolts 20 which secure the plates to the bars 2.

25 Cooperable with the shoes 11 to alternately depress and release said shoes and associated parts to permit action of the springs 12, are two cam wheels 21 having peripheral cams 22 of uniform circumferential length and uniform radial height, each cam being preferably provided with an abrupt radially disposed rear end having a notch 23. Two proceeding and receding operating yokes 24 straddle the upper portions of the cam wheels 21 respectively and are provided with pins 25 to successively engage the notches 23 and thus intermittently turn the wheels 21 a distance equivalent to the length of one cam 22.

30 In the preferred form of construction, the yokes 24 are carried by a pair of pitman rods 26 which are connected with cranks or eccentrics 27 on a transverse drive shaft 28 mounted in suitable bearings 29; under the landing plate 3. At least one of the cranks 35 or eccentrics 27 is connected with the shaft 28 by a removable pin 30, so that its wrist pin may be either set in alignment with the wrist pin of the other crank or may be opposed thereto. Thus, the two cam wheels 21 may be operated either alternately, or simultaneously, as occasion may dictate. By alternate operation of the wheels, the screen vibrating means is caused to alternately force opposite sides of the screen upwardly 40 against the stops 17, and the screen is more gently vibrated than if both sides are forced simultaneously upward.

45 Attention may here be directed to the fact that when the springs 12 force upwardly on the screen and associated parts, the bars 16 strike the stops 17 before the shoes 11 can strike the lower ends of the cams 22. Thus, excessive wear on the shoes and cams is prevented. By varying the space 31 which exists between either shoe 11 and the low end

of any cam 22, when the bar 10 is raised, it will be seen that the distance which said shoe and associated parts will be depressed by the high end of the cam, may be effectively regulated and thus the intensity of the screen thrust may be varied as occasion may require. To obtain proper relative adjustment of each cam wheel 21 and shoe 11, I prefer to mount said wheel upon a carrying lever 32 fulcrumed at 33 to the adjacent side bar 2 and having an appropriate adjustable connection 34 with said bar, to hold the lever in set position.

50 By providing the construction shown and described, a screen is produced which will be highly efficient and desirable. As excellent results are obtainable from the details disclosed, these details are by preference followed, but within the scope of the invention as claimed, numerous changes may be made.

55 It may here be stated that while, in a sense, the screen is a vibrating screen, it is not of the nature commonly known as a vibrating screen, in which the upward and downward impulses of the screen take place in rapid succession and the material on said screen never moves an appreciable distance from the latter. By my improved arrangement, in which the cam wheels are intermittently driven, a different action is obtained. Each time one of the cams 22 releases the co-acting shoe 11, the adjacent springs 12 come into play to forcibly thrust the screen upwardly, to the limit permitted by the stop bar 17 or its equivalent. This movement of the screen throws the material thereon high into the air and any particles of the material which would otherwise have a tendency to clog the screen are thus thrown upwardly from it, so that clogging is practically impossible. The material falls back on the screen while the latter stands inert, so that such material then sifts through the screen. By the time all of the material thrown into the air has again settled, the cam wheel again functions, so that another forcible impulse will be imparted upwardly on the screen. Thus, it will be seen that my invention distinguishes from the average vibrating screen, in that there is an appreciable lull between the intervals at which the screen is forced upwardly, this lull being obtained by rotating the cam wheel or wheels in a step-by-step manner, permitting said wheel or wheels to remain absolutely inert for a proper period of time after each turning thereof.

60 I claim:

65 1. A screening device comprising a screen, means for thrusting said screen upwardly when said means is moved to a predetermined position and released, a rotatably mounted cam wheel having peripheral cams for so moving and releasing said screen thrusting means, and means for turning

said cam wheel a distance equivalent to the length of one cam at spaced intervals, permitting it to remain inert between such intervals.

5 2. A screening device comprising a screen, means for thrusting said screen upwardly when said means is moved to a predetermined position and released, a rotatably mounted cam wheel having peripheral cams for so moving and releasing said screen thrusting means, and means co-operable with the cams of said wheel for turning the wheel a distance equivalent to the length of one cam at spaced intervals, permitting it to remain 10 inert between such intervals.

3. A screening device comprising a screen, means for thrusting said screen upwardly when said means is moved to a predetermined position and released, a rotatably mounted cam wheel having peripheral cam for so moving and releasing said screen thrusting means, and a proceeding and receding operating member for turning said cam wheel a distance equivalent to the length 15 of one cam at spaced intervals, permitting it to remain inert between such intervals.

4. A screening device comprising a screen, means for thrusting said screen upwardly when said means is moved to a predetermined position and released, a rotatably mounted cam wheel having peripheral cams for moving and releasing said screen thrusting means, and a proceeding and receding operating member co-operable with said 20 cams for turning the wheel a distance equivalent to the length of one cam at spaced intervals, permitting it to remain inert between such intervals.

5. A structure as specified in claim 4; said operating member having a yoke straddling a peripheral portion of the cam wheel, said yoke having a portion to engage the cams of said wheel and turn the latter.

6. A screening device comprising screen thrusting means in two units for spaced parts of a screen, each unit being operable when moved to an inoperative position and released, separate cam wheels for the two units having peripheral cams for moving said units to inoperative positions and then releasing them, and means operable first on one cam wheel and then on the other for intermittently turning said wheels a distance equivalent to the angle between two adjacent cams.

7. A structure as specified in claim 6; said intermittent turning means for said cam wheels being co-operable with the cams of said wheels.

8. A structure as specified in claim 6; said intermittent turning means for said cam wheels comprising a pair of oppositely stroking proceeding and receding members co-operable with said cams.

65 9. A structure as specified in claim 1; to-

gether with means limiting the operative movement of the screen thrusting means to a stroke of less length than the radial height of the cams, and means for relatively adjusting said cam wheel and the cooperating 70 part of the screen thrusting means toward and from each other.

10. A structure as specified in claim 1; together with means limiting the operative movement of the screen thrusting means to 75 a stroke of less length than the radial height of the cams, and an adjustable carrier for said cam wheel movable toward and from the portion of the screen thrusting means which cooperates with said wheel. 80

11. A device of the class described comprising a main frame having parallel side bars formed with downwardly opening notches, spring saddles secured to said bars at the open ends of said notches, transverse 85 screen shaking bars whose ends pass outwardly through said notches, springs in said saddles thrusting upwardly on said transverse bars, longitudinal bars secured to said transverse bars and located at the outer sides 90 of said side bars, and means for alternately depressing and releasing said longitudinal bars.

12. A device of the class described comprising a main frame having parallel side 95 bars formed with downwardly opening notches, spring saddles secured to said bars at the open ends of said notches, transverse screen shaking bars whose ends pass outwardly through said notches, springs in said 100 saddles thrusting upwardly on said transverse bars, longitudinal bars secured to said transverse bars and located at the outer sides of said side bars, shoes carried by said longitudinal bars, and driven cam wheels co-operable with said shoes for alternately depressing and releasing said longitudinal bars. 105

13. A device of the class described comprising a main frame having parallel side 110 bars channeled at their inner sides, transverse screen carrying bars whose ends are movably received in the side bar channels, and means for vertically vibrating said 115 transverse bars.

14. A device of the class described comprising a main frame having parallel side bars channeled at their inner sides, longitudinal screen supporting bars in the side bar channels, projections extending outwardly from said screen supporting bars through openings in said side bars, and means associated with said projections for vertically vibrating said screen supporting 120 bars. 125

15. A device of the class described comprising a main frame having parallel side bars channeled at their inner sides, transverse screen carrying bars whose ends extend movably into the side bar channels, 130

means for vertically vibrating said transverse bars, and stop flanges in the side bar channels in the upward paths of said transverse bars.

5 16. A structure as specified in claim 15; together with guard plates secured against the inner sides of said side bars and con-

tacting with the inner edges of said stop flanges, said guard plates having flanges resting on said stop flanges. 10

In testimony whereof I have hereunto affixed my signature.

HERMAN F. WULLSTEIN.
